CLAIM

The ornamental design for a manifold for angioplasty balloon catheter, as shown and described.

DESCRIPTION

FIG. 1 is a perspective view of a manifold for angioplasty balloon catheter, showing our new design;

FIG. 2 is a side elevational view thereof;

FIG. 3 is a side elevational view thereof, opposite that shown in FIG. 2;

FIG. 4 is a top plan view thereof;

FIG. 5 is a bottom plan view thereof;

FIG. 6 is a front elevational view thereof;

FIG. 7 is a rear elevational view thereof;

FIG. 8 is a perspective view of a second embodiment of FIG. 1;

FIG. 9 is a side elevational view thereof;

FIG. 10 is a side elevational view thereof, opposite that shown in FIG. 9;

FIG. 11 is a top plan view thereof;

FIG. 12 is a bottom plan view thereof;

FIG. 13 is a front elevational view thereof, and

FIG. 14 is a rear elevational view thereof.
